T. H. WRIGHT

SWITCH DEVICE

Filed Sept. 15, 1922

Inventor,
Thomas H. Wright

by Hazard and Miller
ATTORNEYS

UNITED STATES PATENT OFFICE.

THOMAS H. WRIGHT, OF LOS ANGELES, CALIFORNIA.

SWITCH DEVICE.

Application filed September 15, 1922. Serial No. 588,433.

To all whom it may concern:

Be it known that I, THOMAS H. WRIGHT, a citizen of the United States, residing at Los Angeles, in the county of Los Angeles 5 and State of California, have invented new and useful Improvements in Switch Devices, of which the following is a specification.

My invention relates to mono-rail tracks 10 and particularly, although not necessarily, to the type of track embodied in my copending application Serial No. 588,430, filed September 15th, 1922.

It is a purpose of my present invention to 15 provide a switch device for mono-rail tracks which is of simple, durable and efficient construction and which is capable of being operated to arbitrarily direct a mono-rail car from a main track to any one of a plurality of branch tracks.

Although I will describe only one form 20 of switch device embodying my invention, and will point out the novel features thereof in claims, it is to be understood that various changes and modifications may be 25 made without departing from the spirit of the invention and the spirit and scope of the appended claims.

In the accompanying drawings,

30 Figure 1 is a view showing in top plan one form of switch device embodying my invention in applied position with respect to a plurality of mono-rail tracks;

Figure 2 is a vertical sectional view taken 35 on the line 2-2 of Figure 1.

Referring specifically to the drawings, in 40 which similar reference characters refer to similar parts, my invention, in its present embodiment comprises a carriage made up of a plurality of beams or bars 15 rigidly connected in spaced parallelism by means of a supporting structure for mono-rail tracks, and provided with a plurality of 45 grooved wheels 16 mounted for movement over rails 17 connected at their ends to posts 18. In the present instance, the intermediate portion of the carriage is provided 50 with two beams 15 between which are arranged the grooved wheels 16, while the end portions of the carriage are constructed with 55 single beams with the wheels 16 disposed at the outer sides of the beams. Certain of the wheels 16 are connected by a drive shaft 19, such shaft being journaled in the beams 20 and operatively connected to a motor

through the medium of a sprocket and chain connection 21, as clearly shown in Figure 2.

As previously mentioned, the several beams of the carriage are rigidly connected to each other through the medium of mono-rail tracks, and these tracks are in reality track sections, with any number of track sections sustained upon the carriage, depending upon the particular use to which the switch device is adapted to be put. In 60 the present instance, I have shown the carriage as supporting a curved track section 22 and a linear or straight track section 23. In both instances, the track sections and their supporting means are constructed in 65 accordance with the mono-rail track embodied in my copending application hereinbefore referred to.

The switch device is adapted for directing a mono-rail car designated at 24 from a 70 main track 25 to either of a pair of branch tracks designated 26 and 27, respectively. To this end, the rails 17 are arranged at an angle with respect to the several tracks so 75 as to allow of the necessary movement of the carriage in properly positioning the track sections 22 and 23 with relation to the main and branch tracks.

In operation, the carriage of the switch device may occupy any one of two extreme 80 positions, the carriage being propelled to either position through the medium of the motor 20, it being understood that by energizing the motor the shaft 19 will be actuated to effect a driving of the corresponding 85 wheels 16 in one direction or the other, depending upon the direction of rotation of the motor 20. In one extreme position of the switch device, the track section 22 is disposed in connecting relation with respect 90 to the main track 25 and the branch track 27 so that the car 24 can move from the main track to the curved branch. In the other extreme position of the switch device, the track section 23 is disposed in connecting 95 relation with respect to the main track 25 and the branch track 26. In either extreme position of the switch device, the wheels 16 abut the posts 18 so as to properly define the 100 two positions of the carrier.

Although I have shown a switch device particularly adapted for directing a mono-rail car from a main track to either of a pair of branch tracks, it is to be understood 105 that the switch device may be so constructed 110

as to effect the direction of a car from a main track to a multiplicity of branch tracks of either curved or linear form.

I claim as my invention:

5. 1. A switch device comprising rails, posts at the ends of the rails, a carriage including wheels movable over the rails, said carriage being capable of occupying two extreme positions in either of which the wheels are
- 10 10. adapted to abut the posts, track sections on the carriage, and means for driving the carriage.
- 15 2. A switch device comprising rails arranged in spaced relation to each other, abutment members at the ends of the rails, a carriage including beams, wheels journaled on the beams and movable over said rails, tracks on the carriage, and propelling means for the carriage comprising a motor, a
- 20 shaft connected to certain of the wheels, and means operatively connecting said motor with said shaft.
- 25 3. A switch device comprising spaced rails, posts at the ends of the rails constituting abutments, said rails including two end rails and an intermediate rail, a carriage including two end beams and a number of intermediate beams secured in spaced relation, wheels carried by the beams and movable over said rails, the wheels carried by the intermediate beams being between the
- 30

latter, tracks sustained on the beams, and means for propelling the carriage comprising a motor, a shaft connected to certain of said wheels, and means for operatively connecting said motor with said shaft. 35

4. A switch device comprising spaced rails, said rails including two end rails and an intermediate rail, a carriage including two end beams and a number of intermediate beams secured in spaced relation, wheels carried by the beams and movable over said rails, the wheels carried by the intermediate beams being between the latter, tracks sustained on the beams, and means for propelling the carriage comprising a motor, a shaft connected to certain of said wheels, and means for operatively connecting said motor with said shaft. 40

5. A switch device comprising spaced rails, said rails including two end rails and an intermediate rail, a carriage including two end beams and a number of intermediate beams secured in spaced relation, wheels carried by the beams and movable over said rails, the wheels carried by the intermediate beams being between the latter, tracks sustained on the beams, and means for propelling the carriage. 45

In testimony whereof I have signed my name to this specification. 50

THOMAS H. WRIGHT.
